UNITED STATES PATENT OFFICE.

WILLIAM EVANS KEHOE, OF SAN FRANCISCO, CALIFORNIA.

DESIGN FOR A DISPLAY FIXTURE.

Application filed April 2, 1923. Serial No. 5,665. Term of patent 7 years.

To all whom it may concern:

Be it known that I, WILLIAM EVANS KEHOE, a citizen of the United States, residing at the city and county of San Francisco, State of California, have invented a new, original, and ornamental Design for Display Fixtures, of which the following is a specification, reference being had to the accompanying drawing, forming part thereof.

Fig. 1 is a front elevation of a display fixture showing my new design.

Fig. 2 is a side elevation of the same.

I claim:

The ornamental design for a display fixture, as shown.

WILLIAM EVANS KEHOE.
